UNITED STATES PATENT OFFICE.

CHARLES E. VAN DOORN, OF IRONDEQUOIT, NEW YORK.

MOP-WRINGER.

1,132,752.

Specification of Letters Patent. Patented Mar. 23, 1915.

Application filed July 20, 1914. Serial No. 851,868.

To all whom it may concern:

Be it known that I, CHARLES E. VAN DOORN, of Irondequoit, in the county of Monroe and State of New York, have invented certain new and useful Improvements in Mop-Wringers; and I do hereby declare the following to be a full, clear, and exact description of the same, reference being had to the accompanying drawings, forming a part of this specification, and to the reference-numerals marked thereon.

My present invention relates to mop wringers and more particularly to mop wringers of the type adapted to be detachably mounted upon pails, and it has for its object to provide a simple, strong and efficient device of this nature that can be economically formed of stamped sheet material and will be light and easily assembled.

The improvements are directed more particularly to a novel combination of means for guiding the movable jaw of the wringer toward and from the fixed jaw through the utilization of the component parts of the wringer in a new arrangement.

To these and other ends the invention consists in certain improvements and combinations of parts all as will be hereinafter more fully described, the novel features being pointed out in the claims at the end of the specification.

In the drawings: Figure 1 is a front elevation of a mop wringer constructed in accordance with and illustrating one embodiment of my invention; Fig. 2 is a top plan view thereof, partly in section; Fig. 3 is a central vertical section; Fig. 4 is a side elevation, and Fig. 5 is a section corresponding to Fig. 3, but with the movable parts in a different position.

Similar reference numerals throughout the several figures indicate the same parts.

The main frame or body of the wringer may be stamped and formed from a single piece of sheet metal and comprises a front wall 1 constituting the fixed jaw of the wringer, and end walls 2 turned at right angles therefrom, all of said walls being provided with apertures 3, as usual, for the escape of the expressed water and the wall 1 with corrugations or irregularities, if desired. At the outer margins of the end walls 2, separate supporting plates 4 are attached and fastened as by rivets 5, it being preferable to make these separately for reasons that will hereinafter appear. The said

plates 4 have notches 6 to receive the edge of the pail upon which the wringer is to be mounted, the extensions 7 and 8 adjacent to the notches being adapted to bear against the inner and outer walls of the pail, respectively.

The fixed jaw or wall 1 is provided near its bottom with a horizontal guiding slot 9 preferably formed with an adjacent outwardly extending lip 10 to give strength and an added bearing surface while the end walls 2 have substantially horizontal guides or slots 11 similarly fitted with outstanding lips 12, such slots 11 being at a relatively elevated point with reference to the slot 9.

The movable jaw of the wringer is constituted by a plate 13 approximately coextensive with the wall 1 and having a parallel movement toward and from the latter. Motion is transmitted to it by means of a transverse shaft 14 journaled in bearing openings 15 in the supporting plates 4. Communicating slots 16 with which the openings are provided lead to the edges of the plates 4 through which the ends of the shaft are passed when the latter is mounted before the plates are attached to the end walls 2 by the fasteners 5 and that is a reason for the separate formation of the said supporting plates 4. When the latter are secured in place, the shaft, which has been thus easily assembled, is retained within its bearings and endwise thrust is prevented by suitable collars 17 which may be integral with the shaft.

The shaft is rocked by means of a handle 18 fixed in a socket 19 on one projecting end thereof outside of the adjacent end wall and supporting plate. It carries fixed thereto, two crank arms 20 having bearings 21 that receive the ends 22 of links 23. The opposite outwardly turned ends 24 of the links lie against the movable jaw 13 and are held by bearing straps 25. They are extended outwardly still farther to slidably coöperate with the slots 11 in the end walls 2 as guides. At its bottom edge, the movable jaw 13 is provided with a horizontally turned plate 26 which forms the bottom plate of the wringer and prevents the mop head from slipping through when inserted. This plate coöperates with the slot 9 as a guide and thus the slots 9 and 11 constitute spaced parallel guides that insure a parallel motion on the part of movable jaw 13 relatively to the fixed jaw and prevent the

former from having any tendency to bind. This parallel movement is more efficient than the pivotal movement heretofore often employed and at the same time does away 5 with the great length of the jaw 13 that is there required in order that it may turn on a remote center and approximate parallelism to the fixed jaw. It will be noted, however, that in providing these guides 9 and 10 11, practically no additions are made to the component parts of the wringer, but on the other hand, the results are accomplished by arranging some of the parts to perform the additional functions.

15 The cranks 20 and links 23 constitute toggles and the two extreme positions of the movable jaw shown in Figs. 3 and 5 are themselves thought to amply explain the movement.

20 I claim as my invention:

1. In a mop wringer, the combination with a fixed jaw and a movable jaw and end walls connected with the fixed jaw, of guides on the fixed jaw and the end walls respectively, the last mentioned guide being located above the bottom of the wringer and above the first mentioned guide, devices on the movable jaw coöperating with said guides to give the movable jaw a parallel movement toward and from the fixed jaw and means for imparting motion to the movable jaw.

2. In a mop wringer, the combination with a fixed jaw having a horizontal slot 35 near the bottom thereof, of a movable jaw having a parallel movement toward and from the fixed jaw, means for imparting motion to the movable jaw and a rigidly connected bottom plate on the latter co-operating with the slot in the fixed jaw as a guide.

3. In a mop wringer, the combination with a vertically disposed fixed jaw having a horizontal guide near the bottom thereof, 45 of a movable jaw having a parallel movement toward and from the fixed jaw, means for imparting motion to the movable jaw and a rigidly connected bottom plate on the latter co-operating with the guide on the 50 fixed jaw.

4. In a mop wringer, the combination with a fixed jaw having a horizontal slot near the bottom thereof and end walls connected with the fixed jaw and provided with 55 horizontal guides arranged above the said slot, of a movable jaw having a parallel movement toward and from the fixed jaw,

means for imparting motion to the movable jaw, devices on the latter coöperating with the guides on the end walls, and a rigidly 60 connected bottom plate on the movable jaw coöperating with the slot in the fixed jaw as a guide.

5. In a mop wringer, the combination with a fixed jaw having a horizontal slot near the bottom thereof and end walls connected with the fixed jaw and also provided with horizontal slots located above the first mentioned slot and substantially centrally of 65 said end walls, of a movable jaw having a parallel movement toward and from the fixed jaw, means for imparting motion to the movable jaw, devices on the latter coöperating with the slots in the end walls as guides, and a bottom plate on the movable 70 jaw coöperating with the slot in the fixed jaw as a guide.

6. In a mop wringer, the combination with a fixed jaw having a horizontal slot near the bottom thereof, and end walls connected with the fixed jaw and also provided with horizontal slots, of a movable jaw having a parallel movement toward and from the fixed jaw, means for imparting motion to the movable jaw, toggle links connected to 80 said means and having outwardly turned ends journaled in the movable jaw and also projecting into the slots in the end walls as guides and a bottom plate on the movable 85 jaw coöperating with the slot in the fixed jaw as a guide.

7. In a mop wringer, the combination with a fixed jaw and a movable jaw and end walls connected with the fixed jaw, of supporting plates formed separately from the 95 end walls but fastened thereto along one edge of each to constitute extensions thereof, said supporting plates being provided with bearing openings and with communicating 100 slots leading from the openings to the attached edges of the plates, and means for imparting motion to the movable jaw embodying a shaft journaled in the bearing openings of the supporting plates and adapted to be inserted through the communicating slots before the supporting plates 105 are fastened to the end walls, said end walls operating as closures for the slots to confine the shaft within its bearings.
